UNITED STATES PATENT OFFICE.

FRANK X. SCHWAB, OF BUFFALO, NEW YORK.

KEG.

SPECIFICATION forming part of Letters Patent No. 700,567, dated May 20, 1902.

Application filed February 24, 1902. Serial No. 95,160. (No model.)

To all whom it may concern:

Be it known that I, FRANK X. SCHWAB, a citizen of the United States, residing at Buffalo, in the county of Erie and State of New York, have invented certain new and useful Improvements in Kegs, of which the following is a specification.

This invention relates to an improved keg in which the staves are joined to each other by tongue-and-groove connections, said tongues being of equal size throughout and terminating abruptly a short distance from the stave ends, and said grooves being of equal depth throughout and corresponding in form to the tongues which fit therein. The head parts are also joined by similar tongues and grooves.

The object of the invention is to form a keg which shall be absolutely liquid-tight and which will stay tight, all of which will be fully and clearly hereinafter described and claimed, reference being had to the accompanying drawings, in which—

Figure 1 is a horizontal section through a keg on or about line *a a*, Fig. 2. Fig. 2 is a vertical section through a portion of a keg on or about line *b b*, Fig. 1. Fig. 3 is a plan view of a portion of the head of a keg. Fig. 4 is a side view of same. Fig. 5 is a section through the head on line *c c*, Fig. 3. Fig. 6 is a section through one of the staves on or about line *d d*, Fig. 8. Fig. 7 is an inside view of two of the staves before being bent. Fig. 8 is a side view of one stave before being bent. Fig. 9 is an inside view of two staves after being bent. Fig. 10 is a side view of one of the staves after being bent.

Referring to the drawings for the details of construction, like numerals designate like parts.

The improved keg is composed of a series of staves, two heads, and hoops. The staves 1 are each made by machinery and are cut so that they are of equal size and identical form. Each stave when first cut to form is flat and has curved side edges 2. A longitudinal tongue 3, of equal size throughout and curved cross-section, is formed integral with the stave and projects from one side edge thereof, terminating near each end of the stave in an abrupt shoulder 4. A longitudinal groove 5 is cut in the opposite side edge, which is of equal depth throughout and correspondingly

terminates near each end of the stave in an abrupt shoulder 6. In the art tapered tongues and grooves have been employed, as have also removable ribs loose in the grooves with curved shoulders; but neither of these forms are efficient in preventing leaks of liquid, especially when under pressure, since the curved shoulders are only in engagement when the staves are held closely together and separate from each other when the staves separate, so that the loosening or springing of the hoops, and consequently partial separation of the staves, will produce intervening spaces, which serve as outlets for the liquid contained therein. The advantages of the abrupt shoulders is that the shoulders are in engagement even when the staves become slightly separated from any cause, and thus materially aid in maintaining a tight joint, which is of vital importance in a keg of this description designed for holding beer, ale, or similar liquids. A transverse groove 7 is formed on the interior of the stave near each end thereof, which when the staves are assembled constitutes the annular groove or pocket in which the parts of the head are supported. The tongue 3 and groove 4 of each stave extend beyond the chime, as shown in Figs. 7, 8, 9, 80 and 10, thereby providing a tight continuous interlocking joint, which prevents any leak through those portions of the staves between the heads.

The heads 8 are each in several parts, which are joined by tongue-and-groove connections similar to those described with reference to the staves, the tongues 9 being of equal size throughout and terminating a short distance from the ends of the head parts in abrupt shoulders 10 and the grooves 11 being of equal depth and corresponding in cross-section to the cross-section of the tongues, said grooves also terminating a short distance from the ends in abrupt shoulders 12.

In assembling this keg the staves are bent by machinery to give a middle bulge to the same and also bring the edges of adjacent staves in close contact throughout and force the tongues into the grooves. The hoops are then forced on the keg ends to hold the staves in their bent condition and the keg parts in assembled position.

The main advantage of this improved keg

is that it is absolutely tight and remains permanently tight. As the tongues and grooves do not extend from end to end of the staves and head parts, but terminate a short distance from the ends thereof in abrupt shoulders, all the staves and head parts necessarily fit perfectly when properly assembled.

Another advantage of this construction is that the meeting shoulders of the tongues and grooves of the staves brings the ends of all the staves in exact alinement.

I claim as my invention—

1. A keg having its staves provided with curved side edges and an integral tongue projecting from one of said side edges of each stave of equal size and thickness throughout which terminates near each end of the stave in abrupt shoulders, and a longitudinal groove in the other side edge of equal depth through-

out corresponding in size and form to the tongue and terminating in an abrupt shoulder at each end, substantially as set forth.

2. In a keg, heads, a series of staves having transverse grooves in their inner faces forming chimes for said heads and side tongue-and-groove connections which terminate at points beyond the transverse grooves and within the ends of the staves in abrupt opposed shoulders, substantially as described.

3. A keg having heads, and a plurality of staves with chimes in which the heads seat and interlocking tongues and grooves which extend beyond the chimes and terminate within the ends of the staves.

FRANK X. SCHWAB.
